CLAIM

The ornamental design for a mirror for a magnetic resonance imaging machine, as shown and described.

DESCRIPTION

1. Mirror for magnetic resonance imaging machine
- 1.1 is a perspective view of the mirror for magnetic resonance imagine machine showing our new design;
- 1.2 is a left side elevational view thereof;
- 1.3 is a right side elevational view thereof;
- 1.4 is a front elevational view thereof;
- 1.5 is a rear elevational view thereof;
- 1.6 is a top plan view thereof; and
- 1.7 is a bottom plan view thereof.
